UNITED STATES PATENT OFFICE

WILLIAM K. LIGGETT, OF COLUMBUS, OHIO, ASSIGNOR TO THE JEFFREY MANUFACTURING COMPANY, OF COLUMBUS, OHIO, A CORPORATION OF OHIO

LOADING DEVICE

Application filed January 18, 1926, Serial No. 82,047. Renewed May 17, 1929.

The present invention relates to certain new and useful improvements in loading machines, and particularly to loading devices adapted to control the flow of loose material from a supply hopper to an elevator bucket of the type commonly known as a skip hoist.

The especial object of this invention is to provide a combined loading chute and control valve arranged to be operated by movement of a skip bucket, to permit material to flow into said bucket when in loading position, and to prevent such flow when the bucket is removed from loading position.

The means whereby I attain this object are fully set forth in the following specification, and illustrated in the accompanying drawings of which

Fig. 1, is a side elevation of a skip bucket and loading chute embodying my present invention.

Fig. 2, is a fragmentary sectional view taken along line II—II of Fig. 1.

Fig. 3, is a diagrammatic elevation of a material storing plant having a skip hoist equipped with the devices of my present invention, showing the relation of the skip bucket and loading chute to the other elements of the installation.

Fig. 4, is a sectional view taken in the central vertical plane of Fig. 1, showing the relation of the material flowing through the spout to the spout and bucket while in loading position.

Fig. 5, is a fragmentary sectional view, similar to Fig. 4, showing the relation of the material within the spout to said spout when it is in closed position.

Like numerals refer to similar parts in the several figures.

As shown in the drawing the numeral 1, indicates a skip, or bucket, which is preferably of a generally rectangular cross section. The skip 1 is provided with two axles 2 and 3 upon which are journaled the traction wheels 4 and 5 adapted to travel between the vertical guide rails 6 and 7 to guide movement of the skip between the points of loading and discharge. Fixed to the bottom of the skip 1 is a transversely extending shaft

8 to the projecting ends of which is connected the bail 9 to which the hoisting rope 10 is attached. When the rope 10 is tensioned by the hoisting devices, which are not shown in the drawing, the skip 1 is raised, the guide rollers 4 and 5 guiding it to the discharge position, in the installation here illustrated, above the storage bin 11. The relation of the guide rails 6 and 7, and of the rollers 4 and 5 is such that when the skip reaches the upper extremity of its travel it will be turned bottom upwards to discharge its contents into said bin, and will be automatically returned to its material carrying position as it moves downward. Such devices are well understood in the art, and, since they form no part in the present invention, further description and illustration is not thought to be required at this time.

Adjacent the foot of the guideways 6 and 7 is a supply hopper 12, which may be of any preferred form and dimensions, and which may be associated with any preferred source of material supply. As here illustrated the hopper 12 is positioned beneath a railroad track 13 to receive material discharged through the bottom of the railroad car 14 in the common and well known manner. Opening out of the hopper 12, is an open trough, or chute, 15 the bottom of which is inclined at an angle upon which the material to be loaded will flow from the hopper 12. Supported upon the pivot member 15^a is a conductor spout 16, which is also an open trough, adapted, when in its lower position, to conduct loose material from the hopper 12 to the skip bucket 1, and when in its upper position to close the end of the chute 15 and thereby prevent the flow of material therefrom. A counter weight 17 fixed to the conductor spout 16 acts to hold the spout in its closed position against the pressure of material in the chute 15.

Attached to the upper forward corners of the skip 1 are brackets 18 having rollers 19 adapted to engage the operating cams 20 and 21 of the conductor spout 16. The cams 20 and 21 are preferably formed integral with the bracket castings 22 fixed to the lower end of the spout 16. As the skip descends the

rollers 19 engage the lower cams 20 to depress the outer end of the spout 16, which overlaps the top edge of the skip to permit material to flow thereinto. When the skip 1 moves upwardly the rollers 19 engage the upper cams 21 to lift the outer end of the spout 16 to its closed position to thereby cut off the flow of material from the hopper 12. The counter weight 17 retains the spout in its closed position until it is moved therefrom by downward movement of the skip. The baffle plate 23, fixed to the spout 16 in position to partially close its outer end, serves to limit the discharge of material from said spout. The proportions of these parts are such that, when the skip bucket 1 is in its loading position, the discharge end of the spout will extend downwardly into said bucket to such a position that the accumulation of material in the bucket will stop the flow of material in the spout when a predetermined load has been delivered, the baffle plate 23 is in such position as to prevent spillage of material from the spout as the bucket ascends. The bottom plate of the spout 16 is bent downwardly at 15^b to form a lip, or scraper, adapted to push the loose material rearwardly of the skip bucket 1, as the spout 16 moves upwardly to its closed position, and thereby form a cavity 30 into which the material flowing from the spout may fall, preventing such material from spilling over the forward edge of the bucket as it ascends. As the spout 16 approaches its closed position any material remaining therein falls back into the trough 15, the sides of which are of sufficient height to retain such material until the bucket is in position to receive it from the spout 16.

It is to be understood that I do not limit myself to the precise construction here described and illustrated, since it is obvious that the devices may be subject to wide variations as to details without departure from the spirit of my invention.

45. What I claim is:—

1. In a machine of the class described, the combination with a receptacle reciprocable in a fixed path, of a spout pivotally supported adjacent said path adapted when in one position to conduct material to said receptacle, means actuated by movement of said receptacle to turn said spout about its pivotal support to a material conducting position or to a material obstructing position, and a downwardly turned lip formed on said spout as and for the purpose set forth.

2. The combination with a receptacle adapted to travel up and down in a fixed path, and a bin having an outlet adjacent said path, of a spout pivotally mounted at said outlet, means actuated upon up and down movement of said receptacle to turn said spout about its axis respectively to a position to conduct material from the bin to the receptacle or to a position to obstruct the flow of

material from the bin, and a downwardly turned lip on the lower extremity of said spout and forming a continuation of the bottom wall thereof, said lip being so disposed as to project inwardly of the receptacle beyond the adjacent edge thereof when the receptacle is in loading position. 70

3. The combination with a receptacle adapted to travel up and down in a constant path, and a bin having an outlet adjacent said path, of an open topped spout pivotally mounted at said outlet, means actuated upon up and down movement of said receptacle to turn said spout about its axis respectively to a position to conduct material from the bin to the receptacle or to a position to obstruct the flow of material from the bin, an upright baffle extending across the mouth of the spout with its lower edge spaced above the bottom wall of the trough, and a downwardly turned lip on the lower extremity of said spout and forming a continuation of the bottom wall thereof, said lip being so disposed as to project inwardly of the receptacle beyond the adjacent edge thereof when the receptacle is 80 85 90 in loading position.

4. In apparatus of the class described, the combination with a receptacle element reciprocable in a substantially vertical path, of a spout element pivotally supported adjacent said path and adapted when in a downwardly inclined position to extend over and into said receptacle element to discharge material therein and when in an upwardly inclined position to cut off such discharge, and means to move said spout element from one position to the other comprising spaced cam surfaces on one of said elements and a projection on the other element adapted to cooperate with one or the other of said cam surfaces depending upon the direction of movement of said receptacle element to positively move said spout element about its pivotal axis. 95 100 105

5. In apparatus of the class described, the combination with a receptacle element reciprocable in a substantially vertical path, of a spout element pivotally supported adjacent said path and adapted when in a downwardly inclined position to extend over and into said receptacle element to discharge material therein and when in an upwardly inclined position to cut off such discharge, and means to move said spout element from one position to the other comprising a bracket on one of said elements having spaced cam surfaces and a projection on the other element adapted to cooperate with one or the other of said cam surfaces depending upon the direction of movement of said receptacle element to positively move said spout element about its 110 115 120 125 pivotal axis.

6. In apparatus of the class described, the combination with a receptacle element reciprocable in a substantially vertical path, of a spout element pivotally supported adjacent 130

said path, means acting upon downward movement of the receptacle element to swing said spout element into a downwardly inclined position in which its end extends over and into said receptacle element to discharge
5 therein, cam and follower members on said elements respectively, and a bracket maintaining the member associated with the spout element at a distance below the bottom wall of that element, said members cooperating to 10 positively swing said spout element to an upwardly inclined position upon upward movement of the receptacle element.

7. In apparatus of the class described, the combination with a receptacle element reciprocable in a substantially vertical path, of a spout element pivotally supported adjacent said path and adapted when in a downwardly inclined position to extend over and into said receptacle element to discharge material 15 therein and when in an upwardly inclined position to cut off such discharge, and means to move said spout element from one position to the other comprising spaced cam surfaces associated with one of said elements and a projection on the other of said cam surfaces depending upon the direction of movement of said receptacle element to pivotally move said spout element about its pivotal axis, and 20 a bracket fixed to the spout element and maintaining the spout element moving means associated with that element at a distance below the bottom wall thereof.
25

In testimony whereof I have hereunto set my hand.
